GATE FOR RAILWAY-CROSSINGS.

1,261,433.

Specification of Letters Patent.

Patented Apr. 2, 1918.

Application filed April 20, 1917. Serial No. 163,458.

To all whom it may concern:

Be it known that I, SAMUEL R. PAYNE, a citizen of the United States, residing at Protection, in the county of Comanche and 5 State of Kansas, have invented certain new and useful Improvements in Gates for Railway-Crossings, of which the following is a specification.

My invention relates to new and useful 10 improvements in gates and more particularly to railway gates for use in grade crossings, the primary object of my invention being the provision of a gate for this purpose which will be automatic in its action, 15 both its movement to active and its movement to inactive position being controlled by the passage of trains along the track.

Another object which I have in view is the 20 provision of a gate including a pair of barriers disposed one at either side of the track which, when in inactive position, extend vertically at one side of the track and which, in active position, swing downwardly to extend across the road that crosses the track in 25 a horizontal position.

In this connection, a still further object resides in mounting the gate so that it will 30 swing to active position by gravity against the action of certain counterweights which nearly counterbalance the weight of the 35 gate and in which means operable by a passing train is provided for throwing the gate or barriers off from dead center so that they will swing to active position.

Another object which I have in view is 40 the provision of a barrier actuating mechanism capable of releasing the barrier and also operating to compress certain springs which will subsequently raise the barriers when the train has passed.

Another object which I have in view is 45 the provision of means which will absolutely prevent the barrier raising mechanism from coming into operation until the train has passed beyond the road which the barriers guard.

With these and other objects in view, my 50 invention will be more fully described, illustrated in the accompanying drawings, and then specifically pointed out in the claims which are attached to and form a part of this application.

In the drawings:

Figure 1 is a side elevation of a railway

crossing equipped with my improved gate, 55 the barriers being shown in raised position;

Fig. 2 is a plan view of the mechanism shown in Fig. 1;

Fig. 3 is a fragmentary side elevation, illustrating the train actuated mechanism; 60

Fig. 4 is a plan view of the structure shown in Fig. 3;

Fig. 5 is a fragmentary side elevation of the gate actuating mechanism proper;

Fig. 6 is a sectional view taken on the line 65 6—6 of Fig. 5, looking in the direction of the arrows.

Fig. 7 is a fragmentary vertical sectional view taken on the line 7—7 of Fig. 5, looking in the direction of the arrows. 70

Corresponding and like parts are referred to in the following description and indicated in all the views of the drawings by the same reference characters.

In order to clearly illustrate my railway 75 crossing gate and its manner of operation I have shown it in connection with a track including rails 10 arranged to guard a cross road 11. A supporting base 12 extends transversely beneath the track at one side 80 of the road, as best shown in Fig. 2 of the drawings, and at its ends carries a pair of spaced vertical standards 13 which support the barriers and their actuating mechanisms. The barriers 14 are of the usual or any preferred 85 structure and at their pivoted ends are formed with laterally offset heads 15 substantially segmental in shape and having their peripheral faces formed with gear teeth 16. Pivots 17 are passed through these 90 heads concentric with the teeth and also serve as securing means for brackets 18. The standards 13 at their upper ends have rearward extensions or arms 19 and shafts 20 journaled in these arms carry pinions 21 which mesh with the teeth of the barrier 95 heads 15 and also with the teeth of segments 22 rotatably supported upon shafts 23 journaled in the arms 19. These segments 22 are formed with cam extensions 24 engageable with the inclined faces 25 of counterweights 26 which are slidably mounted 100 between the ends of the arms and which are supported by attachment to levers 27 pivoted, as shown at 28, to the brackets 18, preferably, to additionally brace the arms, tie bolts 29 connect their free ends, as clearly shown in Figs. 5 and 6. Brackets 30 are

secured to the standards 13; as will be later explained, and have their upper ends slotted at 31 to receive rivets, bolts or other suitable devices 32 which are passed through the free ends of the levers 27 so that the brackets may steady and support the levers during their swinging movement and may also operate to raise the levers and their counterweights through downward movement of the brackets, although permitting a more rapid upward movement of the brackets than swinging of the lever at certain times as will be pointed out.

A shaft 33 is journaled in the standards 13, extending transversely beneath the track, and mounted upon this shaft between each pair of standards is an eccentric disk 34 carrying an eccentric strap and arm 35 which projects upwardly between the standards and which, at its upper end, carries a pivot 36 which connects it with a cam block 38. Bolts 37 are passed through this cam block, through slides 39 operating in vertical slots 40 formed in the standards and through the brackets 30 and are secured by nuts 37. By this arrangement, it will be clear that turning of the shaft 33 will act through the eccentric and eccentric arm to cause reciprocation of the cam block 38 and links 31. As a consequence, the shaft 33 is turned in a counterclockwise direction, as indicated by the arrow in Fig. 5, the cam portion or nose 41 of the block, which seats in a V-shaped notch 42 formed in the adjacent face of the barrier head, will act against the lower face of the notch to swing the barrier head and move the barrier out of vertical position. This same movement of the eccentric arm will act through the brackets 30 or links to swing the lever 27 and its counterweight 26 upwardly so that the counterweight will not engage the cam member 24 and the gate may continue its movement to horizontal position. During the latter part of this movement, however, the counterweight 26 will engage the cam 24 to check and cushion the movement of the gate so that it will not be injured. An arm 43 extends rearwardly from the eccentric disk 34 and carries a second counterweight 44 which is adjustably mounted on the arm to coöperate with the counterweight 26 in properly balancing the barrier and in assisting to return the barrier to vertical position, as will be later explained.

Inasmuch as the shaft 33 will act through both its eccentrics and their cam blocks 38, it will be seen that the barriers 14 will be released and will swing to active position simultaneously. Preferably, each barrier is provided with an electric signal light 45 and if this is the case wires 46 may be run from this light along the barrier to contacts 47 mounted upon the lower or forward edge of

the barrier and insulated from each other. Corresponding contacts 48, carried by one of the standards 13, are disposed in position to be engaged by the contacts 47 when the barrier is in lowered position and current supply wires 49 may be led from any suitable source of electrical energy to these latter contacts. Under these circumstances, the lights will be automatically energized when the barriers are in active position while their circuits will be opened as soon as the barriers start back to inactive position.

Coöperating with the above described mechanism is an operating mechanism adapted to be actuated through engagement by a passing train and preferably supported by one of the rails 10 of the track. This operating mechanism includes a pair of substantially L-shaped trips 50 which are pivoted to the outer face of the rail, one at a suitable distance at either side of the road or crossing 11 and which, under normal conditions, have their longer arms projecting above the level of the top of the rail and at an incline toward the crossing. A plurality of brackets 51 are secured at one end to the base of the rail and at their opposite end carry pins 52 which operate in slots formed in ramps 53 disposed against the outer face of the rail 10 and occupying the entire distance between the trips and the crossing. By this means, the ramps are supported for limited vertical movement. Preferably, the ends of the ramps adjacent the trips are cut-away to provide seats 54 for the trips when they are depressed so that a depression of the trips will bring them into engagement with the seats and, consequently, will cause depression of the ramps. Centering rods 55 are anchored at one end in the web of the rail 10 at spaced intervals and at their other ends operate through guide ears 56 projecting from the ramps and helical springs 57 surrounding these centering rods and engaging between the rail web and ears serve to normally hold the ramps in elevated position.

The pins 52 also pass through slots 58 formed in cam heads 59 of lifting levers 60 and the cam faces of these heads engage beneath pins 61 carried by the ramps. A series of links 62 connect the lower ends of the trips 50 and lower ends of the lifting levers 60 at either side of the crossing and a link 63 connects that lifting lever nearest the crossing at one side with the upper end of a cam lever 64 pivoted intermediate its length upon a bracket 65 carried by the base 12, while a link 66 connects that lifting lever nearest the crossing at the other side with the lower end of the cam lever 64. Under these conditions, it will be apparent that a train approaching the crossing in

either direction will engage one of the trips 50 and cause depression not only of that trip and the adjacent ramp but also of the more remote trip and ramp. Preferably, 5 braces 67 are provided at suitable intervals along the rail and formed with slots 68 to receive pins 69 carried by the ramps to assist in guiding and supporting them.

The cam lever 64 is formed about its pivot point and lower terminal with a cam extension 70 which engages a crank arm 71 carried by the shaft 33 so that whenever the cam lever 64 is swung in a clockwise direction, due to depression of either trip, the 10 crank arm 71 and, consequently, the shaft 33 will be turned in a counterclockwise direction. This crank arm 71 at its free end swings between spaced arms of a U-shaped extension 72 of the bracket 65 and carries 15 a centering rod 73 which is pivoted to the crank arm and free for rotation through the end of the extension 72. A heavy helical spring 74 is supported by this centering rod 73 engaging at one end against the extension of the bracket and at its other end against the crank arm to normally hold the crank arm in the position shown in Fig. 3, in which position the eccentrics 34 are correlated parts are disposed as shown in 20 Fig. 5.

From the foregoing description, when taken in connection with the drawings, the operation of my improved railway gate or barrier will be readily understood. A train approaching in either direction will engage one of the trips 50 and depress it, thereby depressing both ramps and the other trip. The depression of the trip will act through the links, connecting it with the cam lever 25 64 to swing it in such a manner as to turn the shaft 33 in a counterclockwise direction. This turning of the shaft will act through the eccentric arms 35 and cam blocks 38 to tilt the barriers 14 out of vertical position.

This turning of the shaft will also cause 30 compression of the spring 74 so that it will offer no resistance to the lowering of the barriers. The counterweights 26 and 44 will, however, prevent such rapid falling of 35 the barriers as might cause their injury. Obviously, as long as any portion of the train remains between the trips, both trips and ramps will be held in depressed position and the barriers will remain in lowered position. As soon, however, as the train has 40 passed the second trip, the spring 74 will act to force the cam lever 64 to normal position which will act through the various links to raise the trips and through the 45 lifting levers to raise the ramps, this action being, of course, greatly assisted by the ramp springs 57. This raising of the trips and ramps releases the shaft 33 so that it 50 may return to original position, such move-

ment being accomplished partially through 65 the action of the counterweight 44 and partially through the action of the counterweight 26 operating on the cam portion of the toothed sector 22 which will in turn act through the pinion 21 and toothed head 15 70 of the barrier 14 to swing the barrier to elevated position. The lowering of the weighted end of the lever arm 27, of course, operates through the links or brackets 30 to assist in moving the eccentric arm up- 75 wardly to the position shown in Fig. 5 which also operates to turn the rock shaft 33 to normal position.

Although I have illustrated and described my invention in all its details of construction, it will of course be understood that I do not wish to be limited to such details, but reserve the right to make any changes, within the scope of the appended claims, without in the slightest degree departing 80 from the spirit of my invention.

Having thus described the invention, what is claimed as new is:

1. In a railway gate, a pivoted barrier having a toothed head concentric with its 90 point of pivotal support, a pinion meshing with the teeth of the head, a toothed cam member meshing with the pinion, a lever arm pivotally mounted, a counterweight carried by the lever arm and engaging the cam 95 member whereby when the lever arm is released the counterweight may operate to turn the cam member and through the pinion and toothed head of the barrier to swing the barrier toward a vertical position, a rock 100 shaft, and operative connection between the rock shaft and barrier head and between the rock shaft and lever, whereby movement of the rock shaft in one direction will raise the counterweight and tilt the barrier out of 105 vertical position, while movement of the rock shaft in the opposite direction will act to swing the barrier toward vertical position and will release the lever arm.

2. In railway crossings, a pivotally supported barrier, a rock shaft adapted when turned to cause the barrier to swing to active position and when countercounted to cause the barrier to swing to inactive position, and 110 train controlled means for swinging the rock shaft, said means including a crank arm on the shaft, a cam lever engaging the crank arm, trips disposed in the path of the wheels of a train, operative connection between the trips and cam lever, and ramps disposed in 115 the path of the wheels of a train and having operative connection with the cam lever to hold it in the position to which it is moved through depression of a trip.

3. In railway crossings, a pivotally supported barrier, a rock shaft adapted when turned to cause the barrier to swing to active position and when countercounted to cause 120

the barrier to swing to inactive position, and train controlled means for swinging the rock shaft, said means including a crank arm on the shaft, a cam lever engaging the crank arm, trips disposed in the path of the wheels of a train, operative connection between the trips and cam lever, ramps disposed in the path of the wheels of a train and having operative connection with the cam lever to hold it in the position to which it is moved through depression of a trip, and means for automatically returning the ramps and trips to normal position when they are released by the train.

4. In a railway gate, a pivoted barrier having a toothed head concentric with its point of pivotal support, a pinion meshing with the teeth of the head, a toothed cam member meshing with the pinion, a lever arm pivotally mounted, a counterweight carried by the lever arm and engaging the cam member whereby when the lever arm is released the counterweight may operate to turn the cam member and through the pinion and toothed head of the barrier to swing the barrier toward a vertical position, a rock shaft, and operative connection between the rock shaft and barrier head and between the rock shaft and lever, whereby movement of the rock shaft in one direction will raise the counterweight and tilt the barrier out of vertical position, while movement of the rock shaft in the opposite direction will act to swing the barrier toward vertical position and will release the lever arm, said means including an eccentric on the rock shaft, an eccentric arm carried thereby, a cam block pivoted to the eccentric arm and having a cam portion engaging in a notch in the barrier head, slides connected to the cam block to restrict it to vertical movement, and

links connected to the slides and having slotted pivotal connection with the free end of the lever.

5. In a railway gate, a pivoted barrier having a notched head, means engaging the notch in the head and movable to partially tilt the barrier from vertical position, means controlled by the head engaging means for causing continuation of this movement of the barrier, track obstacle controlled means for actuating the head engaging means, and means for returning the head engaging means to normal position to cause raising of the barrier.

6. In a railway gate, a pivoted barrier having a toothed head concentric with its point of pivotal support, a toothed segment adapted when turned to cause turning of the head and formed with a cam projection, a counterweight engaging the cam projection to cause turning of the toothed sector when the counterweight is released, and track obstacle controlled means for releasing the counterweight and starting initial swinging of the barrier whereby further swinging of the barrier will be caused through engagement of the counterweight with the cam portion of the sector.

7. In a railway gate, a pivoted barrier, a trip adapted to be depressed by the wheels of a passing train, operative connection between the trip and barrier whereby depression of the trip will cause lowering of the barrier, and a ramp rail depressible though engagement with the wheels of a train and engaging said trip to hold it in depressed position as long as the wheels of the train engage the ramp rail.

In testimony whereof I affix my signature. 80

SAMUEL R. PAYNE. [L.S.]
